RETRIEVING MECHANISM

Henry Bosch, Jr., San Francisco, Calif.

Application June 9, 1936, Serial No. 84,305

7 Claims. (Cl. 242—107)

This invention relates to retrieving or re-winding mechanisms such as spring re-wound window shades, drums, and reels having cords wound thereabout, and like devices, and especially to means operable in conjunction therewith to prevent a too rapid retrieving or re-winding action.

Practically all window shades in common use today consist of a roller about which the window shade is wound. The roller is supported with relation to the upper portion of a window casting by means of a pair of brackets, one bracket serving as a bearing for one end of the roller, and the other bracket as a support for the opposite end of the roller and also as an anchor member for a rod which extends a substantial distance into the roller. The end of the rod which enters the bracket is flattened and extends into a slot in the bracket and as such is non-rotatable. This rod serves the following functions: First, that of supporting one end of the roller; secondly, that of supporting a helical spring; third, that of functioning as an anchor member for one end of the spring. The other end of the spring is secured to the roller, hence when the shade is unwound or lowered the rotational movement of the roller will wind the spring and produce sufficient tension to re-roll the roller when the window shade is to be raised. On the end of the roller adjacent the rod is mounted a pair of gravity actuated pawls which are adapted to engage with ratchet teeth carried by the rod. These pawls will only function when the roller is slowly rotated and they serve the function of securing the roller against re-winding action when the window shade has been lowered.

When it is desired to raise the shade it must be pulled downwardly a slight distance and then raised quickly as one or another of the pawls would otherwise engage, and if the window shade is purposely or accidentally released the roller will re-wind with an exceedingly rapid action; or, plainly speaking "run away" as there is nothing to restrict the re-winding action of the helical spring. There is a stick at the lower end of the window shade and when the shade is fully re-rolled the stick is liable to strike one or another of the supporting brackets and tear the shade and if it does not do so it will run around and around the roller until the spring becomes unwound. Hence, when the shade is to be lowered the next time it will be found that there is not sufficient tension in the spring to cause re-winding of the shade and it must then be taken down and partly re-wound or tensioned before it is

possible to retrieve or re-roll the window shade; hence there are two major objections, either that of unwinding the spring or that of tearing the stick from the shade cloth.

The object of the present invention is generally to improve the operation of retrieving or re-winding devices of this character; to provide in conjunction with a shade roller, a reel, or like structure, a brake or stop mechanism which is automatically released to permit unwinding of the shade when a pull is exerted thereon, said brake or stop mechanism also remaining released when a yielding resistance is applied to the shade so as to permit re-winding of the shade but said brake or lock mechanism being automatically applied or locked the moment pull on the shade is released; to provide a shade roller, reel, or like structure in which the re-winding spring may be placed within the shade roller or reel or at a point exterior thereof, for instance, in one of the shade roller supporting brackets; and, further, to provide a brake or lock mechanism in which the brake is applied by the tension of the re-winding spring and released by relieving said tension.

The invention has several different applications and different forms which are shown by way of illustration in the accompanying drawings, in which—

Fig. 1 is a cross section taken on line I—I of Fig. 2;

Fig. 2 is a central longitudinal section of a reel mechanism;

Fig. 3 is a plan view partially in section taken on line III—III of Fig. 1;

Fig. 4 is a front view partially in section of a window shade and its actuating mechanism;

Fig. 5 is a plan view of Fig. 4, partially in section;

Fig. 6 is an end view of the bracket 31 and the housing 42 formed integral therewith;

Fig. 7 is a cross section taken on line VII—VII of Fig. 4;

Fig. 8 is a front view partially in section of a window shade showing a modified form of the mechanism disclosed in Fig. 4;

Fig. 9 is a cross section taken on line IX—IX of Fig. 8;

Fig. 10 is a plan view of the bracket 70 and the housing 50 formed integral therewith;

Fig. 11 is a cross section taken on line XI—XI of Fig. 8.

The invention, briefly described, comprises a stationary support in the form of a housing, a

bracket, or the like; a first rotor in the form of a shade roller, a reel, or the like, rotatably mounted in the support; a second rotor in the form of an arm, a disc, or the like, normally rotatable in unison with the first-named rotor but said rotors having a limited rotary movement with relation to each other; a spring or like mechanism for re-winding the first rotor and mechanism actuated by the limited rotational movement of the first and second rotors with relation to each other for either releasing or locking said rotors against release with relation to the stationary support.

One form which the invention may assume is shown in Figs. 1, 2 and 3. In this instance a spring actuated reel is disclosed which is adapted to be placed in the base of a lamp, in the wall, or partition, of a building, or in any place where an electrical extension cord or the like is required.

The mechanism consists of a cylindrical-shaped housing 2 having end walls 3 and 4. Journalized between said walls centrally of the housing is a shaft 5 and secured thereon is a reel 6 about which is wound an extension cord 7. Secured to one face of the reel is a disc 8 of insulating material and secured to said disc are two conductor rings 9 and 10, to which the terminal ends of the extension cord are connected. Electric current is delivered to the housing by a cable 11 which is connected with two terminals carried by an insulating block 12. These terminals also carry brushes 13, one in engagement with each conductor ring and current is thus delivered to the extension cord 35 whether the reel is rotating or stationary.

Secured interior of the housing is a drum 14 which serves two main functions, first that of an anchor for the outer end of a re-winding spring 15, the inner end of which is secured to shaft 5 40 to rotate the same and the reel carried thereby and, secondly, that of a brake drum as will hereinafter appear.

Supported by the shaft 5 and interposed between the reel and the drum is a disc 16. This disc is connected to the reel by a rod 17 pivotally attached to the reel as at 18, and having its other end slidably and extending through a lug 19, pivoted on the outer end of an arm 20 which is secured to the disc 16. The rod carries an adjustable collar or nut 21 between which and the lug 19 a compression spring 21a is interposed. A collar 22 on the outer end of the rod limits the movement of the rod and hence the disc 16 with relation to the reel. The entire connection will normally cause the disc 16 to rotate in unison with the reel but it permits a limited movement of the disc with relation to the reel or vice versa. This movement is important as it is utilized to either apply or release an external band brake such as indicated at 24. The band brake encircles the drum 14 and its free ends are attached to a lever 25, as shown in Fig. 1, said lever being pivotally attached to the disc as at 26 and being provided with a forked extension which straddles a pin 27 secured to the reel.

In actual practice if the reel carries an electric extension cord the free end of said cord will pass through an opening 28 in the housing and will be provided with a plug 29, or like connection. When it is desired to extend the cord it is merely necessary to grasp the plug 29, or the cord itself, and to pull it outwardly. In so doing the reel rotates and spring 15 will be put under greater tension. When the cord has been extended as far as desired the reel is automatically locked

against rotation and the cord may thus be used. On the other hand, if it is desired to re-reel the cord it is necessary first of all to exert a slight pull on the cord and then to apply yielding resistance; that is, resistance which permits the spring to re-reel the cord yet does not permit the reel to run away.

The reel proper will now be referred to as the first rotor and the disc 16 as the second rotor. It has already been stated that the first and second rotors will rotate in unison with each other either when the cord is being pulled off or extended and also when the cord is being re-reeled. A limited free movement of one rotor with relation to the other is, however, permitted through the connection formed between the two rotors as shown by the numerals 18 and 22 in Fig. 1. When the brake band 24 is applied arm 25 will assume the full line position shown in Fig. 1, and rod 17 the full line position shown in the same figure. On the other hand, if a pull is exerted on the extension cord the spring surrounding the rod 17 will cause the parts 18 and 19 to separate, or in other words will cause a limited rotation of the disc in a direction opposite to that of the pull on the cord. This movement of the disc or second rotor relative to the reel or first rotor causes the lever 25 to swing about its pivot 26 and assume the position shown in dotted lines in Fig. 1. The brake band will thus be released and as a further pull is exerted on the cord both the reel and the disc, or in other words, the first and second rotors will rotate in unison. Such rotational movement in a reverse direction will also take place as long as a yielding resistance is applied to the cord but if the pull on the cord is suddenly released the tension of the re-winding spring 15 is so great that it instantly overcomes the tension of the spring surrounding the rod 17, or in other words overrides the same. In that case the reel moves faster than the disc and thereby causes the parts 18 and 19 to approach each other. This motion reverses the position of the lever 25 and the brake band is instantly applied thereby locking the reel and disc or the first and second rotors against rotation. The action of releasing and locking is to all intents and purposes instantaneous. It is thus possible to extend the cord to any point desired and to lock it in that position and it is also possible to re-reel the cord at any time desired. That is, all of the cord or as little of it as may be desired.

In Figs. 4 to 7 the invention is shown as applied to a window shade. In this instance it will be understood that the shade roller will be provided with the usual internal re-winding spring 29 and that the shade roller proper will be supported in brackets 30 and 31 at opposite ends. The bracket 30 is of the usual type as the flat or spear end of the roller projects into it and is secured against rotation therein. The bracket 31, on the other hand, is different as it carries a cylindrical housing or extension which functions as a brake drum and also as a housing and support for the first and second rotors, as will now be described.

The first rotor comprises a shaft 32 journalized as at 33 in one end of the housing and at the opposite end in a closure plate 34. This shaft is slotted as at 35 to receive the flat end 36 of a pin which is secured in the shade roller. The shaft is also provided with a disc 37 which will be referred to as the first rotor, as it is directly connected with or actuated by the re-winding spring 29. The second rotor indicated at 38 is cylind-

5 drical in shape and is supported by shaft 32. It has a limited rotational movement with relation to the first rotor, said limited movement being controlled by a spiral spring 39 anchored at the inner end to the shaft 32 and at the outer end to the second rotor, said last-named anchorage being formed by slotting the second rotor, as at 40, and forming a projecting end on the spring 39 which extends into the slot.

10 The brake employed in the present instance is of the internal expanding type. It comprises a helical spring 41 which surrounds the second rotor and which is interposed between said second rotor and the inner face of the housing indicated at 42. This spring functions as a brake band, one end of the spring having a projecting end 42a which extends into an opening in the disc 31 while the opposite end of the spring has a projecting end 42b which projects into the slot 40. Whenever there is rotational movement between the first and second rotor the spring 41 will either be contracted or expanded. When contracted it permits free movement of both rotors with relation to the housing and when expanded it forms a brake with relation to the inner face 42 of the housing.

If it is desired to lower the shade it is merely necessary to grasp it by the shade stick and to exert a downward pull. The moment the pull 30 is sufficient to overcome the tension of re-winding spring 29, spring 39 causes the second rotor to move in a direction to contract the spring 41 and thereby release the brake. Further pull on the shade causes both rotors to rotate in unison 35 and causes winding of the spring 29. The moment the pull on the shade is released spring 29, which is much more powerful than spring 39, overcomes the action of that spring and there will again be a rotary motion between the two 40 rotors causing expansion of the spring 41 and thereby causing it to function as a brake as it expands and grasps the inner surface 42 of the housing, thereby locking both rotors against rotation.

45 In Figs. 8 to 11 a still different form of structure suitable for attachment to a shade roller, a reel, or the like, is disclosed. The structure consists of a cylindrical housing 50 closed at one end and provided with a bearing 51. The opposite 50 end of the housing is normally closed by a closure plate 52 having a bearing 53. Extending through the housing and journaled in the bearings 51 and 53 is a shaft 54 on which is formed a disc 55, which will be referred to as the first rotor, 55 as it is driven and actuated by a re-winding spring hereinafter to be referred to. Carried by the shaft 54 is a disc 56, which will be referred to as the second rotor. This disc has a limited rotary movement with relation to the first rotor 60 just as in the other structures, said limited movement being controlled by a spiral spring 57 interposed between the rotors and anchored at the inner end to the shaft of the first rotor and at the outer end to the second rotor as shown at 58. 65 The outer face of the disc 55, or in other words, the first rotor, is provided with two cam surfaces such as indicated at 59 and 60. Two balls, such as shown at 61, are placed on the cam surfaces and are held against lateral movement with 70 relation thereto, first by the adjacent face on the second rotor 56 and, secondly, by a disc or end plate 62. A pair of pins 63 are secured to the face of the second rotor and project into the path followed by the balls 61. The tension of 75 the spring 57 is such that it will tend to rotate

the second rotor with relation to the first rotor a sufficient distance to cause the pins to engage the balls and normally hold them at the end of the respective cam tracks or in the positions shown in Fig. 9. The balls function as locking or braking members between the first rotor and the housing as they will engage the inner face of said housing when the first rotor overcomes the tension of the spring 57 and rolls the balls outwardly on the cam tracks to a point where the balls will bind between the cam track and the inner face of the housing as shown by dotted lines at 61a. In this position the balls will lock the first and second rotor against rotation with relation to the housing. In most instances, in fact in both of the structures heretofore described, the re-winding spring is carried either by the shade roller or some similar means.

In the present instance the re-winding spring is carried within the housing 50 between the disc 62 and the closure plate 52. A multiple or tandem type of spring is employed, the springs being of the spiral or ordinary clock spring type, as shown in Figs. 8 and 11. The springs are indicated at 65 and 66. The inner end of the spring 65 is secured to the shaft 54, the outer end thereof is secured to a housing 67. This housing has a hub 68 which is freely rotatable on the shaft. The second spring has its inner end anchored to the hub 68 while the outer end of said spring is 30 anchored to the housing at the point indicated at 69. Shaft 54 is slotted at one end to receive the flat end 71 of a shaft, or whatever it may be. By inserting a flat end member such as a screw driver, or the like, and rotating the shaft 54 in 35 the proper direction, the two springs may be wound to any tension desired and obviously the power of those two springs is much greater than that of the spring 57. In actual operation let it be assumed that the housing 50 is provided with brackets, such as shown at 70 see Fig. 9. In that instance it may be connected with an ordinary shade roller and the usual re-winding spring within the shade roller may be entirely eliminated. That is, one end of the shade roller will merely 40 have a pin which is freely rotatable in the bracket 45 30a, such as shown in Fig. 8, while the other end of the shade roller will have a flat end shaft to project into the slot 71 of shaft 54. By pulling on the shade, shaft 54 will rotate in a direction to apply further tension to the springs 65 and 66 and when the pull on the shade is released the tension of these springs will instantly reverse the rotation of the first rotor 55 causing it to rotate a predetermined distance with relation to the second rotor and thereby cause the balls 61 to roll up the inclined cam tracks to a point where they wedge or bind and at that point the two, together with the shade roller, will be locked. Again, by merely exerting a slight pull on the shade roller, that is, a pull sufficient to overcome 55 the tension of the springs 65 and 66, free movement of the first rotor with relation to the second rotor will again take place and the tension of the spring 57 will cause the second rotor and the pins 63 carried thereby to push the balls back to the low point of the cam tracks, thus freeing the rotors and permitting free rotation of the shade rotor as long as a pull is applied.

60 By the structure here disclosed it is possible to 70 very materially simplify the construction of the standard type of shade rollers now in use as the internal re-winding spring may be entirely eliminated and so may the anchor rod to which it is secured. The pawls and ratchet usually em- 75

ployed are also eliminated as they are substituted by the ball 61 and the cams 59 and 60; the re-winding spring being substituted by the springs 65 and 66. Obviously the structure shown in Figs. 8 to 11 may also be applied to reels of any character, whether it be for power extension cords, clothes lines, tapes, and any other similar use, as it would only be necessary to connect the shaft of the reel with the slotted end 71 of shaft 54, and while this and other features have been more or less specifically described and illustrated, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:

20 1. In a retrieving mechanism, an elongated flexible member, a rotor to which one end of said flexible member is secured and about which it is wound and from which said flexible member may be unwound by exerting a pull on the free end thereof, means connected with the rotor for rewinding the flexible member when it has been unwound, a stationary brake drum, a cooperating brake connected with the rotor to secure the rotor against rotation, a second rotor normally rotatable in unison with the first-named rotor, said rotors having a limited rotary movement with relation to each other, and means actuated by the relative rotational movement of the two rotors for automatically applying the brake if a pull 35 on the flexible member is released and for releasing the brake when a pull is exerted on the flexible member.

2. In a retrieving mechanism, an elongated flexible member, a rotor to which one end of said flexible member is secured and about which it is wound and from which said flexible member may be unwound by exerting a pull on the free end thereof, means connected with the rotor for rewinding the flexible member when it has been unwound, a stationary brake drum, a cooperating external brake band carried by the rotor to secure the rotor against rotation, a second rotor normally rotatable in unison with the first-named rotor, said rotors having a limited rotary movement with relation to each other, and means actuated by the relative rotational movement of the two rotors for automatically applying the brake band if a pull on the flexible member is released, and for releasing the brake band when 55 a pull is exerted on the flexible member.

3. In a retrieving mechanism, an elongated flexible member, a rotor to which one end of said flexible member is secured and about which it is wound and from which said flexible member may be unwound by exerting a pull on the free end thereof, means connected with the rotor for rewinding the flexible member when it has been unwound, a stationary brake drum, a cooperating internal expanding brake member carried by the rotor to secure the rotor against rotation, a second rotor normally rotatable in unison with the first-named rotor, said rotors having a limited rotary movement with relation to each other, and means actuated by the relative rotational movement of the two rotors for automatically applying the internal expanding brake member if a pull on the flexible member is released and for releasing the internal expanding brake member when a pull is exerted on the flexible member.

4. In a retrieving mechanism, an elongated flexible member, a rotor to which one end of said flexible member is secured and about which it is wound and from which said flexible member may be unwound by exerting a pull on the free end thereof, means connected with the rotor for rewinding the flexible member when it has been unwound, a stationary brake drum supporting the rotor and spaced therefrom, a cam face formed on the rotor, a roller member interposed between the cam face and the drum and normally engageable with the drum to lock the rotor against rotation, a second rotor normally rotatable in unison with the first-named rotor, said rotors having a limited rotary movement with relation to each other, and means actuated by the relative rotational movement of the two rotors for automatically releasing the roller member with relation to the drum when a pull is exerted on the flexible member and for bringing the roller member back into locking position with relation to the drum when the pull on the flexible member is released.

5. In a retrieving mechanism, an elongated flexible member, a rotor to which one end of said flexible member is secured and about which it is wound and from which said flexible member may be unwound by exerting a pull on the free end thereof, a second rotor connected to the first rotor and normally rotatable in unison with the first rotor, said rotors having a limited rotary movement with relation to each other, means for actuating the first rotor to rewind the flexible member when it has been unwound, and mechanism actuated by the relative rotational movement of the two rotors for automatically locking the rotors against rotation if the pull on the flexible member is released.

6. In a retrieving mechanism, an elongated flexible member, a rotor to which one end of said flexible member is secured and about which it is wound and from which said flexible member may be unwound by exerting a pull on the free end thereof, a second rotor, a spring interposed between the first and second rotors to cause them to normally rotate in unison, said spring permitting a limited rotary movement of the rotors with relation to each other, means for actuating the first rotor to rewind the flexible member when it has been unwound, mechanism actuated by the relative rotational movement of the two rotors for automatically locking the rotors against rotation if the pull on the flexible member is released, and means for releasing the rotors when a pull is exerted on the flexible member.

7. In a retrieving mechanism, an elongated flexible member, a rotor to which one end of said flexible member is secured and about which it is wound and from which said flexible member may be unwound by exerting a pull on the free end thereof, a second rotor, a spring connecting the first and second rotors to cause them to normally rotate in unison, said spring permitting a limited rotary movement of the rotors with relation to each other, a spring for rewinding the flexible member when it has been unwound, locking mechanism for normally securing the rotors against rotation, said locking mechanism releasing the rotors when a pull is exerted on the flexible member and locking the rotors against rotation when the pull on the flexible member is released.
